United States Patent Office

Des. 201,722
Patented July 20, 1965

201,722

ADDRESS PRINTING MACHINE OR THE LIKE

John J. Van Acker, Chesterland, and Darwin S. Crouser,
Mentor, Ohio, assignors to Addressograph Multigraph
Corporation, Cleveland, Ohio, a corporation of
Delaware

Filed Sept. 17, 1964, Ser. No. 81,772

Term of patent 14 years

(Cl. D64—11)

Fig. 1

Fig. 2

Fig. 3

Fig. 4

FIG. 1 is a front and right side perspective view of an address printing machine or the like embodying our new design;

FIG. 2 is a front perspective view thereof;

FIG. 3 is a top plan view; and,

FIG. 4 is a left side perspective view thereof.

We claim:

The ornamental design for an address printing machine or the like, substantially as shown.
